No. 36,357.

Patented June 9, 1903.

UNITED STATES PATENT OFFICE.

BERNE NADALL, OF KINGSTON, ENGLAND, ASSIGNOR TO THE LINOTYPE COMPANY, LIMITED, OF LONDON, ENGLAND.

DESIGN FOR A FONT OF PRINTING-TYPE.

SPECIFICATION forming part of Design No. 36,357, dated June 9, 1903.

Application filed May 14, 1902. Serial No. 107,370. Term of patent 14 years.

To all whom it may concern:

Be it known that I, BERNE NADALL, a citizen of the United States, residing at Kingston, in the county of Surrey, England, have invented a new, original, and ornamental Design for a Font of Printing-Type, of which the following is a specification.

My new, original, and ornamental design for a font of printing-type is illustrated in the accompanying drawing, which represents a typographical impression of the entire font.

What is claimed, and desired to be secured by Letters Patent, is—

The ornamental design for a font of printing-type as shown.

In testimony whereof I affix my signature in presence of two witnesses.

BERNE NADALL.
